INVENTOR:

Hermann Merkel,
BY
Seiner G. Wells,
ATTORNEY,

UNITED STATES PATENT OFFICE.

HERMANN MERKEL, OF ST. LOUIS, MISSOURI.

HYDROCARBON-BURNER.

SPECIFICATION forming part of Letters Patent No. 666,148, dated January 15, 1901.

Application filed November 11, 1899. Serial No. 736,715. (No model.)

To all whom it may concern:

Be it known that I, HERMANN MERKEL, a citizen of the United States, residing at the city of St. Louis, in the State of Missouri, have 5 invented a new and useful Improvement in Hydrocarbon-Burners, of which the following is a specification.

Figure I is a side elevation of a hydrocarbon-burner constructed in accordance with 10 the principles of my invention. Fig. II shows a modification. Fig. III shows a second modification. Fig. IV shows a horizontal section on the line IV IV of Figs. V and I. Fig. V is a vertical section on the line V V of Fig. 15 IV. Fig. VI shows a third modification. Fig. VII is a horizontal section of the line VII VII of Fig. VI.

Referring to the drawings in detail, the cylinder 1 constitutes the principal feature 20 of my invention, and in form it remains unchanged in all of the views. The cylinder 1 is a casting and is cored to form the mixing-chamber 2, which is largest at its center. The internal shoulder 3 is formed at the upper 25 end of the cylinder 1 and supports the flame-screen. As seen from the inside or looking downwardly, there is a band around the mixing-chamber, and the shoulder 3 is the upper end of this band. The slits 4 are 30 cut vertically from the upper end of the cylinder 1 and form gas-openings leading from the mixing-chamber through the band. Recesses 5 are formed in the outer surface of the cylinder below the plane of the shoulder 3, and the slits 4 communicate with said 35 recesses. The vertical ribs 6 separate the recesses. The bead 7 forms a shoulder to support the chimney frame or gallery, and the vertical portion 8, extending from the bead 40 7 to the recesses 5, fits within the band of the gallery. Below the bead 7 the portion 9 of the cylinder is contracted in size.

In Fig. I the nipple 10 is formed integral with the lower end of the cylinder 1 and is 45 internally screw-threaded to be attached to the supply-pipe. The arm 11 extends downwardly from the nipple 10 to a position below the cylinder 1, said arm being inclined substantially at an angle of forty-five degrees, and a valve-casing 12 is formed upon 50 the lower end of the arm 11. The arm 11 is drilled to form the passage 13, which leads

from the supply-pipe to the valve 12. The eye 14 is formed integral with the arm 11 and is designed to receive the hook on the end of the alcohol-torch. The valve 12 discharges into the mixing-chamber 2, and the gas formed within the mixing-chamber leads upwardly, and a portion of the gas passes outwardly through the slits 4 and burns within 60 the recesses 5. The mantle is lowered to a position around the recesses 5, and the subflames in the recesses 5 are within the mantle, thus serving the double purpose of assisting in heating the mantle and heating the metal 65 of the cylinder 1 very hot, said metal serving as a conductor to lead the heat downwardly to the gasolene within the nipple 10 and the arm 11. The subflames within the recesses 5 are below the flame-screen, which rests upon 70 the shoulder 3, and within the mantle I prefer to form the gas-openings leading to the recesses 5 by using slits 4, as shown in Figs. I, II, III, and V; but these gas-openings may be formed by boring holes 15, as shown in 75 Fig. VI, said holes being formed through the metal between the ribs 6. Any means by which gas is led to the recesses 5 will serve the purpose.

In Fig. II the pipe 16 is screwed into the 80 nipple 10. The horizontal arm 17 leads from the lower end of the pipe 16 to a position below the mixing-chamber, and the valve-casing 12 is formed integral with the arm 17. This construction is equivalent to the construction shown in Fig. I, the only difference being the screw-threaded connection.

In Fig. III the lower end of the cylinder 1 is attached to the valve-casing 12 and has air-openings 18 formed through its wall horizontally. The nipples 19 and 20 extend in opposite directions from the valve-casings 12 and are designed to receive the supply-pipes. The eye 14 is formed integral with the valve-casing and one of the nipples. The drop-cup 95 21 is formed integral with the stuffing-box 22 of the valve-casing 12.

The principal feature of my invention is the cylinder 1, cored to form the mixing-chamber 2 and having the recesses 5 in its 100 outer surface below the plane of its flame-screen and having gas-openings leading from the mixing-chamber through the wall of the cylinder 1 to the recesses 5, so that the gas

burns within the recesses 5 below the plane of the flame-screen and within the lower end of the mantle. It is a well-known fact that very little heat is imparted to the metal of the cylinder 1 by the flame above the flame-screen; but a very little gas burning within the recesses 5 directly against the metal of the cylinder 1 and within the lower portion of the mantle will heat the cylinder 1 to a very high temperature, and thus the sub-flames being within the mantle do not produce a waste of gas. The ribs 6 serve as guides for the band of the gallery, the outer face of said ribs being in alinement with the outer face of the portion 8, which rests within the band of the gallery, so that said band may be moved upwardly without danger of its being tipped and breaking the mantle or tipping the chimney off.

20 I claim—

1. In a hydrocarbon-burner, a hollow cylinder forming a mixing-chamber, said chamber being enlarged at its center, and said cylinder having recesses in its outer surface, and 25 openings leading from the recesses to the mixing-chamber, and there being vertical ribs between said recesses to guide the chimney-frame, substantially as specified.

2. In a hydrocarbon-burner, a hollow cylinder forming a mixing-chamber, said cylinder having recesses in its outer surface and gas-openings leading through its wall from the mixing-chamber to the recesses; there being vertical ribs between the recesses to 35 guide the chimney-frame, and there being an enlargement below the recesses to support the chimney-frame, substantially as specified.

3. In a hydrocarbon-burner the hollow cylinder cored to form a mixing-chamber, and having the recesses in its outer surface, and 40 having the band on its inner surface opposite the said recesses, and having openings leading through its wall from the recesses to the mixing-chamber, and having the bead below the recesses, substantially as specified. 45

4. In a hydrocarbon-burner a hollow cylinder forming a mixing-chamber, and having recesses in its outer surface, and having a band on its inner surface opposite the said recesses and having gas-openings leading 50 through its wall from the recesses to the mixing-chamber, and having an enlargement below the recesses to support the chimney-frame, substantially as specified.

5. In a hydrocarbon-burner a hollow cylinder forming a mixing-chamber, and having recesses on its outer surface, and having a band on its inner surface opposite the said recesses, and having gas-openings leading 55 through its wall from the recesses to the mixing-chamber, substantially as specified. 60

6. In a hydrocarbon-burner a hollow cylinder forming a mixing-chamber, and having recesses in its outer surface, and having a band on its inner surface opposite the said 65 recesses, and having vertical gas-openings leading through its wall and the said band, from the recesses to the mixing-chamber, substantially as specified.

HERMANN MERKEL.
